FIG. 7.

FIG. 1 is a perspective view of our universal joint tester as seen in position of normal use;

FIG. 2 is a top plan view thereof, showing in broken lines part of a drive shaft;

FIG. 3 is a front elevational view thereof showing a portion of a drive shaft and U-joint in broken lines;

FIG. 4 is an end elevational view looking from the right of FIG. 3; and

FIG. 5 is the other end elevational view looking from the left of FIG. 3; and

FIG. 6 is a back side elevational view thereof;

FIG. 7 is an alternate embodiment of the tester wherein the only difference resides in the orientation of the movable horizontal spring clamp handle carrying the dial gauge unit to the right of the embodiment shown in FIG. 6.

The broken line portions of the drawings are shown for illustrative purposes only.

We claim:

The ornamental design for a universal joint tester, substantially as shown and described.
